SPRAYING APPARATUS

Albert O. Price, Dover, Ohio, assignor of one-fifth to Otto L. Buzard, Uhrichsville, Ohio

Application January 6, 1931. Serial No. 507,018

7 Claims. (Cl. 137—145)

My invention relates broadly to spraying apparatus and more particularly to a compact construction of automatic intermittently controlled spraying apparatus for handling a predetermined amount of fluid at predetermined time intervals under pressure.

One of the objects of my invention is to provide a construction of automatic and intermittent fluid operating apparatus which may be connected to the usual water supply main for intermittently spraying fluid at predetermined time intervals.

Another object of my invention is to provide a construction of fluid control apparatus which may be interposed between a connection to a fluid supply and a spraying device for intermittently and automatically spraying fluid at predetermined time intervals.

Still another object of my invention is to provide a compact apparatus unit adapted to be connected between a fluid supply system and a spraying device with a pressure control device adapted to intermittently actuate a lever system for opening a valve to a spray line at periodic intervals for effecting an intermittent spraying operation.

A further object of my invention is to provide an apparatus unit of portable construction including a fluid reservoir and pressure regulator controlled thereby with an inlet connection to a fluid supply system and an outlet connection to a valve system adapted to be intermittently controlled by the pressure regulator for effecting a spraying of fluid at predetermined time intervals.

A still further object of my invention is to provide an arrangement of balanced and tensioned lever system for fluid spraying apparatus whereby an intermittent change of pressure may be employed to control the operation of a valve connected to a fluid spray line for effecting an intermittent spraying operation at predetermined time intervals.

Other and further objects of my invention reside in the construction of control mechanism for a fluid spraying system as set forth more fully in the specification hereinafter following by reference to the accompanying drawings, in which:

Figure 1 schematically shows the arrangement of the apparatus of my invention interposed between a fluid pressure supply line and a spraying apparatus; Fig. 2 is a side elevation of the control apparatus of my invention drawn upon a somewhat enlarged scale; Fig. 3 is a top plan

view of the apparatus shown in Fig. 2; Fig. 4 is a central vertical longitudinal sectional view showing the control apparatus in normal position with the supply valve on the extreme left opened to admit fluid pressure to the apparatus for filling up the reservoir on the apparatus; Fig. 5 is a bottom plan view of the apparatus shown in the preceding figures with arrows indicating the intake and discharge connections for the fluid; Fig. 6 is a central longitudinal sectional view of the apparatus showing the reservoir partially filled in the course of operation of the spraying apparatus; Fig. 7 is a transverse vertical sectional view through the control apparatus on line 7—7 of Fig. 2; and Fig. 8 is a transverse sectional view through the apparatus of my invention on line 8—8 of Fig. 2.

The apparatus of my invention is intended for intermittent spraying of golf greens, flower gardens, vegetable gardens, lawns, etc., and is also adapted for connection between a fluid supply line and a supply line which may extend to any number of spraying units mounted, for example, on vegetable display stands for maintaining the vegetables in a fresh condition. The apparatus of my invention is portable and may accordingly be used for many different purposes where it may be desirable to automatically and intermittently deliver a predetermined amount of fluid at predetermined intervals under pressure without waste of fluid. My invention provides a portable unit including a reservoir and a pressure control valve actuated by the fluid within the reservoir to correspondingly control a balanced lever mechanism adapted to actuate a valve to a spray line when a predetermined pressure has been established within the fluid reservoir.

Referring to the drawings in detail, the apparatus of my invention is shown mounted upon a channel shaped base A having fluid inlet valve 2 at one end and a spray outlet valve 12 at the opposite end. A connection is made to the water supply faucet or tap indicated at C through a suitable hose which includes in series therewith a pressure regulator valve 1 which is in turn connected with the intake valve 2 at the tap connection 2c. The intake valve 2 is a needle valve device having a hand control wheel thereon suitably calibrated with respect to a fixed marker for adjustment for the obtaining of required pressure. The calibrated scale is placed upon the face or peripheral edge of the adjusting wheel of the hand valve indicated at 2a and operated with respect to the marker 2b.

to the required position. By reason of the calibration of the handle wheel 2a, this wheel may be reset at the same place from time to time in order that the required amount of water may be passed through the apparatus within a given length of time. From the needle valve 2 the water is conveyed through pipe 3 to the T connection 4 (shown more clearly in Fig. 3) into the cylindrical reservoir 5. The reservoir 5 is formed by a tube closed at the upper end and having an annular flange 5a at the base thereof secured to the channel shaped base A by bolts 5b which pass through the peripheral edge of the resilient diaphragm 6 and through the annular supporting ring 5c. Disposed beneath the resilient diaphragm 6, I provide a plunger 7 of oval shape connected to a stem 7a which passes through the guide 7b in the channel shaped support A and is moved vertically under control of the expansion or contraction of the resilient diaphragm 6. The stem 7a of the plunger 7 abuts against the lever 8 as shown. The lever 8 is the right angularly bent member having a horizontal portion extending beneath the channel shaped frame A and upwardly disposed portion integrally connected therewith and projecting vertically adjacent the end of the channel shaped frame A. The lever 8 is pivoted with respect to the base A between a pair of depending angle members 15 attached to the under surface of the base A. The lever 8 is provided with a multiplicity of apertures 8a, 8b and 8c adjacent the end thereof whereby the fulcrum pin 16 may be adjustably located at any one of the several apertures. The remote end of the lever 8 is confined for movement in a vertical path by means of depending angularly shaped guides 17 secured to the under surface of the support A. The lever is also provided with a series of perforations at 8d, 8e and 8f for the attachment of the spring 9 which tends to constantly urge the lever 8 in a vertically upward direction in continuous contact with the end of the stem 7a of plunger 7. The spring 9 extends vertically upward through a tube 18 and connects to an eyelet 19 formed on the end of screw threaded member 20 which may be adjusted through the end 18a of tubular member 18 by means of wing nut 21. The tubular member 18 is secured to the base A by a screw threaded flange 22 bolted to the base A by bolt members indicated at 22a. Buffers are provided around each end of the tubular member 18 as shown at 23 and 24.

It will be observed that the exterior of the tube 18 is screw threaded at each end thereof and that the buffers 23 and 24 are correspondingly screw threaded so that these buffers may be adjusted along tubular member 18 for limiting the angular movement of spring control lever 11. The spring control lever 11 is pivoted at 25 upon angle member 26 which is secured to the spray control valve 12. The lever 11 is bifurcated or formed in two parts which spread around the tube 18 as represented at 27 to allow angular movement of the lever 11. The portions of the lever 11 are again joined on the opposite side of tube 18 and spread to form a T head as shown at 28. The vertically projecting end of the lever 8 is also provided with a T head or laterally projecting member 29 in the upper extremity thereof, and between the remote ends of the T head 29 and the T head 28 I provide coil springs 10 linking levers 11 and 8 together under tension. The fluid outlet

extends from the spray control valve 12 as indicated at 30 and provides a connection for the spray line 13 which connects with any suitable form of spraying device indicated at 14.

When installing the apparatus of my invention for vegetable display stands, the spray line 13 is connected to any number of nozzles which may be readily installed. The reservoir 5 is connected to the spray valve 12 through pipe 31 for supplying fluid to the spray valve 12 when the spray valve is opened under control of the levers 8 and 11. With the arrangement of lever shown in Figs. 1, 2 and 4, the spraying apparatus is cut off and there is no intermittent spray effected at the spraying device 14. In the position shown in Fig. 6, the sprayer control mechanism is shown in actuated condition for the intermittent spraying of fluid from the sprayer device. In the position shown in Fig. 6, the valve stem 32 of sprayer control valve 12 is depressed by the downward movement of lever 11, thereby effecting the intermittent spraying operation of the apparatus. When the pressure in the tank or reservoir 5 fills up slowly through the needle valve 2 to a value more than the tension offered by spring 9 against lever 8, the stem 7a of plunger 7 forces the lever 8 downward. The water in reservoir 5 builds up against a cushion of air which is compressed within reservoir 6 as shown at B. This compression creates a substantial pressure within the reservoir 5 which forces the resilient diaphragm 6 downward as shown at Fig. 6, thereby moving plunger 7 and stem 7a which is attached thereto. The upwardly projecting end of lever 8 is thus pulled down thereby increasing the tension on springs 10 and moving lever 11 by a small increment sufficient to shift the lever 11 overcenter and open the spray control valve 12 by depressing the stem 32. When valve 12 is open, the water from reservoir 5 rushes out through the spray line 13 until the pressure in reservoir 5 has been diminished to such an extent as to allow the reservoir diaphragm 6 to resume normal position as illustrated in Fig. 4, whereupon lever 8 rises under pressure of spring 9, shifting springs 10 upwardly, thereby again unbalancing lever 11 and causing upward angular movement of lever 11 releasing stem 32 and closing valve 12. As valve 12 closes the water through the needle valve 2 again slowly builds up pressure in the reservoir 5 and the cycle is repeated.

In order to spray a large amount of water, it is necessary to either increase the capacity of reservoir 5 or to provide another tank which can be put into use by means of a valve between the tanks. The time period of spraying may be adjusted by controlling the position of valve 2 and also the tension on spring 9 for regulating the amount of water which is sprayed. Further regulations may be obtained by changing the suspension of lever 8 and the connection of spring 9 thereto. That is, the fulcrum 16 may be shifted as well as a change in the connection of spring 9 to the lever 8 is provided. The regulation may be adjusted for any timing from, for example, intervals of two minutes to intervals of two hours.

The operation of the system of my invention is as follows: When the pressure in the supply source slowly builds up a pressure in the reservoir to exceed the pressure caused by the expansion spring 9, the spring 9 expands and allows the main lever 8 to move downward far enough

to carry the secondary lever 11 over center for opening valve 12. When valve 12 is open the liquid in the reservoir is released through the valve to the spray nozzles 14. The pressure in the reservoir is then quickly lowered to equal the tension of the expansion spring 9 allowing the main lever 8 to move upward carrying with it the secondary lever which allows the valve 12 to close. The time intervals between spraying periods are controlled by the adjustment of needle valve 2 between the supply source and the reservoir 5.

I have found the apparatus of my invention extremely practical in its manufacture and construction, and inexpensive of assembly on a quantity production basis.

While I have described my invention in one of its preferred embodiments, I desire that it be understood that modifications may be made and that no limitations upon my invention are intended other than are imposed by the scope of the appended claims.

What I claim as new and desire to secure by Letters Patent of the United States is as follows:

1. Spraying apparatus comprising a supporting structure, a fluid reservoir carried by said structure, means for admitting fluid from a fluid supply source at a predetermined rate to said fluid reservoir, a sprayer valve connected with said reservoir, a pair of pivotally mounted levers, spring means interconnecting the ends of said levers, an actuator extending between one of said levers and said sprayer valve and means contacting with the other of said levers and controlled by the pressure within said reservoir for effecting a shifting movement of said levers under conditions of change of pressure in said reservoir for effecting movement of said valve actuator and maintaining said sprayer valve in open position so long as the pressure in said reservoir substantially exceeds the effect of said spring means.

2. Sprayer apparatus comprising a supporting structure, a fluid reservoir carried thereby, means for admitting fluid at a predetermined rate from a fluid supply source to said fluid reservoir, a sprayer valve connected with said fluid reservoir, a pair of levers, one of said levers being pivoted adjacent one end of said frame structure, the other of said levers being pivoted adjacent the opposite end of said frame structure, said first mentioned lever extending in the direction of said second mentioned lever and having an end portion extending upwardly adjacent the journal of said second mentioned lever, spring means interconnecting the ends of said levers, a valve actuator controlled by said second mentioned lever, and means controlled by the pressure in said reservoir for effecting movement of said first mentioned lever for correspondingly moving said second mentioned lever and shifting said valve actuator for maintaining said sprayer valve open so long as the pressure in said reservoir substantially exceeds the effect of said spring means.

3. Spraying apparatus comprising a longitudinally extending frame structure, a fluid reservoir mounted adjacent one end of said frame structure, means for admitting a predetermined flow of fluid to said reservoir from a fluid supply source, a sprayer valve mounted adjacent the opposite end of said frame structure and connected with said fluid reservoir, a pair of longitudinally extending levers, one of

said levers extending beneath said frame structure and journaled adjacent the reservoir at one end of said frame structure, the opposite end of said lever projecting upwardly to a position above said frame structure, the second of said levers being journaled adjacent said sprayer valve, spring means interconnecting the ends of said lever members for normally maintaining said lever members in a balanced position, a valve actuator for said sprayer valve controlled by said second mentioned lever member and means controlled by the pressure in said fluid reservoir for shifting said first mentioned lever member and unbalancing said second mentioned lever member for effecting movement thereof and shifting said valve actuator for opening said valve for a time period equal to the interval of time during which the pressure of said reservoir substantially exceeds the effect of said spring means.

4. Spraying apparatus comprising a longitudinally extending frame structure, a fluid reservoir mounted adjacent one end of said frame structure, means for admitting a predetermined flow of fluid to said reservoir from a fluid supply source, a sprayer valve mounted adjacent the opposite end of said frame structure and connected with said fluid reservoir, a pair of longitudinally extending levers, one of said levers extending beneath said frame structure and journaled adjacent the reservoir at one end of said frame structure, the opposite end of said lever projecting upwardly to a position above said frame structure, the second of said levers being journaled adjacent said sprayer valve, spring means interconnecting the ends of said lever members for normally maintaining said lever members in a balanced position, independent spring means for maintaining said first mentioned lever member under predetermined tension, a valve actuator for said sprayer valve controlled by said second mentioned lever member, and means controlled by the pressure in said fluid reservoir for shifting said first mentioned lever member and unbalancing said second mentioned lever member for effecting movement thereof and shifting said valve actuator for opening said valve for a time period equal to the interval of time during which the pressure of said reservoir substantially exceeds the effect of said spring means.

5. Spraying apparatus comprising a frame structure, a fluid reservoir mounted on said frame structure, means for admitting fluid at a predetermined rate to said reservoir from a fluid supply source, a sprayer valve connected with said reservoir, a pair of lever members fulcrumed adjacent opposite ends of said frame structure, a valve actuator extending between one of said lever members and said sprayer valve, tension means interconnecting said levers for normally maintaining said levers in equilibrium with said valve actuator in a position closing said sprayer valve, and means controlled by the establishment of a predetermined pressure in said reservoir for unbalancing the equilibrium of said lever members for effecting an operation of said valve actuator for maintaining said sprayer valve open for a time period equal to the interval during which the pressure in said reservoir substantially exceeds the effect of said tension means.

6. Spraying apparatus comprising a frame structure, a fluid reservoir mounted on said frame structure, means for admitting fluid at a

predetermined rate to said reservoir from a fluid supply source, a sprayer valve connected with said reservoir, a pair of lever members fulcrumed adjacent opposite ends of said frame structure, a valve actuator extending between one of said lever members and said sprayer valve, means interconnecting said levers, spring means for subjecting one of said levers to predetermined tension and means controlled by the establishment of a predetermined pressure in said reservoir for overcoming the last mentioned tension means and shifting the position of said last mentioned lever for unbalancing the equilibrium of said second mentioned lever and operating said valve actuator for opening said sprayer valve for a time period equal to the interval during which the pressure in said reservoir substantially exceeds the effect of said spring means.

20 7. Spraying apparatus comprising a frame structure, a reservoir, means for admitting fluid at a predetermined rate to said reservoir from

a fluid supply source, a sprayer valve connected with said reservoir, a pair of levers fulcrumed adjacent opposite ends of said frame structure, each of said levers having limited angular movement, a pair of buffers for limiting the angular movement of one of said levers, a valve actuator controlled by said last mentioned lever for operating said sprayer valve, spring means interconnecting the ends of said levers for maintaining said levers in equilibrium with said valve actuator in a position for closing said sprayer valve, and means controlled by the establishment of a predetermined pressure in said reservoir for shifting one of said levers and unbalancing the equilibrium thereof for operating said valve actuator and opening said sprayer valve for a time period equal to the time interval during which the pressure in said reservoir substantially exceeds the effect of said spring means.
